THREAD TENSIONING MECHANISM FOR
TEXTILE FABRICATING MACHINESAlbert Thost, Womelsdorf, Pa., assignor to The
Nolde and Horst Company, Reading, Pa., a cor-
poration of Pennsylvania

Application November 3, 1941, Serial No. 417,610

5 Claims. (Cl. 66—146)

My invention relates to yarn tensioning mechanism for textile fabricating machines, and more particularly to a new and simplified means for equalizing and jointly regulating the tension of the several yarns simultaneously fed to each section of a usual multi-section knitting machine; my object being to insure greater uniformity and more perfect knitting throughout each machine section, with better and more evenly turned selvage edges and reenforced areas of added yarn in each such section.

In usual multi-section machines aforesaid, the known and common practice heretofore has been to individually tension each yarn by means of a "snapper" therefor having an independently adjusted spring plate pressing on the feeding yarn; and while series of such "snappers" have been heretofore jointly swung to simultaneously relieve the tension of their individual spring plates on the yarn, it has been found impossible to equalize or maintain uniformity of these independent spring tensions, with the result of undesirable lack of uniformity in the separate fabrics knitted on the multi sections of the machine, and more particularly in more or less uneven and ragged selvage edges and reenforced areas.

My present invention relates to new and simplified means that may, if desired, be substituted for the heretofore unsatisfactory "snapper" means with little change otherwise of the machine construction, and it consists essentially of a guide bar or rod extending longitudinally of the machine and across all the multi knitting sections, said bar having separate guide apertures, one for each of the plurality of yarns employed, and means to axially rotate said bar or rod so as to simultaneously form equalized tension bights in all the yarns carried thereby. The nature of my improvements and the manner of their operation will be more fully described hereinafter in connection with the accompanying drawings, and the novel features thereof specifically set forth in the appended claims.

In the drawings:

Fig. 1 is a diagrammatic cross sectional elevation showing a simple embodiment of my invention as applicable to a usual and well known straight bar knitting machine, only such essential parts of the machine being indicated as sufficient to fully disclose the nature and manner of operation of my improved yarn tensioning mechanism.

Fig. 2 is a fragmentary plan view of the two tension rods shown in Fig. 1.

Fig. 3 is an enlarged cross sectional view of my tension bar, the thread guide eye being shown in position to freely pass the feeding yarn.

Fig. 4 is a view corresponding to Fig. 3, showing the guide eye inclined by turning of the rod so as to exert tension on the yarn by forming a bight therein.

Fig. 5 is another view corresponding to Fig. 3, but showing the rod turned further so as to increasingly incline its guide eye to exert greater tension on the yarn than that shown in Fig. 4.

Fig. 6 is a fragmental sectional elevation, corresponding with Fig. 1, but showing a fixed mounting for my tension rods.

Fig. 7 is a cross sectional elevation, corresponding generally to that of Fig. 1, but indicating how my improvements may be simply applied in place of the heretofore commonly used "snapper" tension devices, and operated from the main cam shaft through a positive rack and gear drive connection.

Fig. 8 is a fragmentary enlarged detail of Fig. 7, showing the guide tension rods and their positive drive mechanism.

25 In the drawings my invention is shown as applied to a straight bar knitting machine, but it will be understood that it is not limited to such machine, and that its application to other machines may be readily understood from this disclosure.

The straight bar knitting machine indicated in the drawings, is so well known as to be readily understood from the cross sectional view thereof, and commonly comprises multi-sections each having a straight needle bar fed by one or more carriers, said sections being longitudinally aligned and all jointly operated to simultaneously produce a plurality of like flat knitted fabrics in a usual and known manner.

40 Referring to the drawings, 1 indicates the knitting needles, 2 the usual sinkers and/or dividers, 3 yarn carriers longitudinally reciprocated along their respective sections of needles to feed yarn to the latter, 5 the main cam shaft having cams 45 jointly operating the mechanism for all the knitting sections as heretofore, 6 the bobbins supplying yarn to the several carriers, 7 a usual liquid treating bath for the feeding yarn, and 8 a usual ring tension device, all as heretofore commonly employed and operating in known manner. The term "yarn" herein used, and in the claims, is intended as a generic term for any strand or thread that may be used.

50 My improved yarn tensioning guide member is shown in the drawings in the forms of a rod 10,

extending longitudinally of the machine and of a single length, or component jointly actuated lengths, sufficient to extend across all of the multi knitting sections of the machine. The drawings show also a second like rod 11, as preferably employed to better divide the several yarns fed to each knitting section, and both rods 10 and 11 are shown as having diametral yarn guide eyes 12 disposed along their length so that each section will have its required number of yarns.

It is essential for my present purposes that the rods 10 and 11 shall be turned on their longitudinal axes so as to bend like tensioning bights thereon in all the yarns engaging their several guide eyes 12, and in the drawings I have shown the rods 10 and 11 as mounted in suitable bearings on carrying arms 15, one end of each of the latter being pivotally connected at 16 to a fixed frame member, and the other end of each connected by a link arm 17 to a lever arm 18 having a cam engaging roller 19 and a pivotal support 20. Suitable cams 25, on cam shaft 5 are adapted to jointly swing the levers 18 and arms 15, preferably against the bias of a spring 26, so as to bodily raise and lower the rods 10 and 11. To maintain the rods 10 and 11 from bending, it will be understood that a suitable number of properly spaced arms 15 will be employed with requisite numbers of levers 18 and cams 25 to jointly actuate them, and arms 15 may be united for more accurate joint action as by a longitudinal tie rod 29. The required axial turning of said rods 10 and 11 to tension their yarns, is shown as produced during the bodily raising and lowering movements of said rods, by means of one or more straps or chains 30, each adjustably connected at 31 to a lever arm 18, at one end, and extending around a fixed roller 32, with its other end bifurcated and one end bent around and connected to a drum 13 on rod 10, and the other end bent around and connected to a drum 14 on rod 11. A spring 33 is preferably interposed in said strap length so as to ease any undue strains that may occur. As the levers 18 and arms 15 are jointly raised by their cams 25, a pulling action will be exerted on each strap 30 so as to axially turn the rods 10 and 11 in their bearings on arms 15. A fixed rod 30' may be employed to suitably lead the several threads to their guide eyes 12 in rods 10 and 11.

The treating bath 7, and ring tension devices 8, with perhaps other tensioning means for certain knitting, are more or less constant, but there are times that additional tension is desirable. One added need for increased tension is recognized to take up yarn slack and tighten the loops as the carriers reach the end of their feed tension and reverse their feeding movements, and my improved tension rods 10, and 11, insure the same slack take-up and equalize increased tensions of all the yarns to form like, even, neat selvages, free of projecting loose loops and ragged edges due when individually tensioned yarns have improper tension. Rod 10 may carry the main yarn producing the side edge selvages, and rod 11, may carry added yarn for reinforced areas, which have their own return feed intermediate the fabric width, and in some cases one rod for all yarns may suffice.

In my improved construction the cams 5, are set to act as the carriers reverse their feed to form the selavage edges, and lift levers 18, and through links 17, raise arms 15, with their rods 10, and 11. This lifting of rods 10, and 11, at once takes up any loose slack thrown by the 70

momentum of the carrier, and as the rod thus lifts, strap 30, act as above described to axially turn the rods to form tension bights in the yarns and, as all yarns are equally acted on, uniform tension throughout the machine is assumed.

In some cases it may not be necessary to lift the rods 10, and 11, to take up slack, and in Fig. 6, I have shown the rods 10a and 11a as rotatably mounted in fixed brackets 15a and slack take up 10 and increased tension solely effected by increased turning of rods 10a, and 11a, say to the degree indicated in Fig. 5.

In the knitting machine indicated in Figs. 7 and 8, the tension rods 10b and 11b are shown as 15 substituted for the usual rods heretofore employed and on which the "snappers" were formerly mounted, these rods 10b and 11b being provided with the necessary number of guide eyes 12b, and their rotation to produce tensioning 20 bights, effected by positive means from the main cam shaft 5b. The means employ a simple adaptation of the means heretofore to rock the "snapper" carrying rods, and consists of spring biased cam actuated lever 18b operating an eye 25 rod 40, the upper end of which carries gear rack 41 held by roller 42 in meshed engagement with a half gear 43 on rod 10b. And rod 10b carries a sprocket gear 44 connected by a link or roller chain 45 to a sprocket 46 on rod 11b. It will be 30 noted that rod 10b rotates at a speed determined by its rack gear drive, and that the smaller gear on rod 11b causes the chain 45 to rotate said rod 11b approximately twice as fast as rod 10b, which increased rotation is found desirable for increased 35 tensioning of yarns employed in splicing and like operations.

From the foregoing disclosure it will be readily seen that my improved tensioning mechanism may be readily substituted for the unsatisfactory "snappers" heretofore employed; that it insures equalized and uniform tension of all like 40 employed yarns; and provides for regulating and varying all yarn tensions equally by simply controlling the rotary movements of the tension rods; and that it may be readily adapted to any 45 other type of textile machine to exert equalized controlled tension of a plurality of yarns.

The particular embodiments above set forth and described are merely indicative and may of 50 course be changed and modified within the scope of my invention as defined in the following claims.

What I claim is:

1. A yarn equalizing tensioning mechanism for 55 textile fabricating machines, comprising an axially turnable rod having a plurality of diametral yarn guide eyes, cam controlled means for alining said guide eyes with their engaged yarns to freely pass the latter, and cam means for axially turning said rod so as to incline said guide eyes to their engaged yarns and form like tensioning bights in each rod guided yarn.

2. A yarn equalizing tensioning mechanism for 60 textile fabricating machines, comprising a bodily movable and axially turnable yarn tensioning guide member having a diametral yarn guide eye normally alined with its engaged yarn to freely pass the latter, and means for simultaneously bodily moving and axially turning said guide member so as to angularly incline said guide eye to its engaged yarn and form thereon a slack take-up and tensioning bight in the yarn.

3. In a knitting machine having a row of 65 knitting needles and a yarn carrier reversely traversed along said row of needles to feed yarn

to the latter, a tension mechanism for said yarn, comprising a rod mounted to axially rotate in parallel relation to said row of needles, a diametral yarn guide eye in said rod normally positioned in alinement with its engaged yarn to freely pass the latter, and cam mechanism operative at each reversal of said carrier traverse to axially turn said rod and wind thereon a tensioning bight of yarn.

4. In a multisection knitting machine having sectional rows of knitting needles and a separate carrier reversely traversed along each sectional row of needles to feed yarn to the latter, a common tensioning mechanism for all the separate carrier yarns comprising, a rod extending longitudinally across all of said knitting needle sections and mounted to axially rotate in parallel relation to the latter, a plurality of yarn guide eyes spaced along the length of said rod to feed yarn to the respective carriers, cam means for normally turning said rod to aline its guide eyes with their respective yarns so as to freely pass the latter, and cam means operative at each reversal of the traverse of said carrier to axially

turn said rod and wind thereon equal tensioning bights of all the yarns.

5. In a multisection knitting machine having sectional rows of knitting needles and a separate carrier reversely traversed along each sectional row of needles to feed yarn to the latter, a common tensioning mechanism for all the separate carrier yarns comprising, a rod extending longitudinally across all of said knitting needle sections and mounted to axially rotate and bodily move in parallel relation to the latter, a plurality of yarn guide eyes spaced along the length of said rod to feed yarn to the respective carriers, cam means for normally lowering said rod relatively to said needle rows and simultaneously turning said rod to aline its guide eyes with their respective yarns so as to freely pass the latter, and cam means operative at each reversal of the traverse of said carrier to raise said rod relatively to said needles so as to take up all yarn slacks and simultaneously to axially turn said rod and wind thereon equal tensioning bights of all the yarns.

ALBERT THOST.
